CLAIM

The ornamental design for an air deodorizing apparatus, as shown and described.

DESCRIPTION

FIG. 1 is a perspective view of the front and one side of the air deodorizing apparatus showing my new design;
 FIG. 2 is an elevational view of the front thereof;
 FIG. 3 is an elevational view of the rear thereof;
 FIG. 4 is an elevational view of one side thereof;
 FIG. 5 is an elevational view of the other side thereof;
 FIG. 6 is a plan view of the top thereof; and,
 FIG. 7 is a plan view of the bottom thereof.
